CLAIM

The ornamental design for a steering wheel pad, as shown and described.

DESCRIPTION

FIG. 1 is a top, front and right side perspective view of a steering wheel pad showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The stippling surface shading shown throughout the drawing views represent three-dimensional contours of the design. The broken lines shown throughout the drawings views are for environmental and illustrative purposes and that form no part of the claimed design.
